(57) **CLAIM**

The ornamental design for a heart shaped gemstone, as shown and described.

DESCRIPTION

FIG. 1 is top plan view of a heart shaped gemstone showing my new design;

FIG. 2 is a bottom plan view thereof;

FIG. 3 is a left side elevation view thereof, with the right side elevation being a mirror image thereof;

FIG. 4 is a front elevation view thereof;

FIG. 5 is a rear elevation view thereof;

FIG. 6 is a rear top side perspective view thereof; and,

FIG. 7 is a front top side perspective view thereof.

The broken lines in the drawings depict portions of the heart shaped gemstone and form no part of the claimed design.
